UNITED STATES PATENT OFFICE

91,510

DESIGN FOR A LIGHT FIXTURE

Harry S. Clarke, Long Beach, Calif., assignor to Fritz Ziebarth, doing business as Southwest
Street Company, Long Beach, Calif.

Application November 18, 1933. Serial No. 49,784

Term of patent 7 years

To all whom it may concern:

Be it known that I, HARRY S. CLARKE, a citizen of the United States, and a resident of Long Beach, in the county of Los Angeles and State of California, have invented a new, original, and ornamental Design for a Light Fixture, of which the following is a specification; reference being had to the accompanying drawing, forming a part thereof.

I claim:
The ornamental design for a light fixture, as shown.

HARRY S. CLARKE.
